H. H. WEBER

EGG HOLDER

Filed Jan. 19, 1928

Fig. 1

UNITED STATES PATENT OFFICE.

HEINRICH HUBERT WEBER, OF MASPETH, NEW YORK.

EGG HOLDER.

Application filed January 19, 1928. Serial No. 247,797.

This invention is a holder adapted to support eggs in a manner adapting them to be boiled without the shells becoming cracked or damaged and to thereafter permit the eggs to be readily served without individual handling thereof.

The holder of this invention may also be used to advantage in the dyeing of eggs for Easter and at other times.

10 I am aware that egg holders and boilers have heretofore been suggested, but in the majority of cases the structure is so complicated as not to be highly practical. Furthermore, in most of the prior devices the arrangement is such that the wires which enter into the construction are apt to become bent and distorted in such a way that the device will not properly carry out its functions.

15 The egg boiler of the present invention is of wire basket formation adapted to support the eggs individually. A handle is associated with the structure whereby the whole device may be conveniently positioned in water or dye and as easily removed therefrom, the eggs 20 being supported from contact with one another at all times.

An important feature of the invention resides in the pronounced rigidity of the structure, its simplicity, durability and economy 25 of manufacture.

30 In carrying out the invention, the device is constructed to embody a plurality of pockets equal in number to the number of eggs which it is desired to support. These pockets are 35 formed through the utilization of a single length of wire which is manipulated by suitable wire bending tools and dies so that all portions of the wire lie in the same plane, the wire being bent into a succession of loops 40 forming the egg seats, each loop is provided with a shank and the shank of each loop is a continuation of the shank of the preceding loop. The seats are made circular and the 45 double wires which constitute the shank of each loop are bound together by lengths of wire which simultaneously constitute feet for supporting the seat frame. In other words, the seat frame is supported by feet formed of lengths of wire and the free ends of each of 50 these lengths of wire are bent upwardly and are coiled about the shanks of the loops of the seat forming frame, so that the legs not only serve to support the frame, but simultaneously bind the loops shut so that they cannot 55 open and the frame become distorted. This is an important feature of the present inven-

tion from the standpoint of manufacture. It not only economizes in such manufacture, but produces a very strong and rigid construction. The feet may be reinforced by a wire 60 ring, and a suitable handle is preferably associated with the frame for the purposes stated.

Features of the invention, other than those specified will be apparent from the herein-after detailed description and claims, when 65 read in conjunction with the accompanying drawings.

The accompanying drawing illustrates one practical embodiment of the invention, but the construction therein shown is to be understood as illustrative only, and not as defining the limits of the invention.

70 Figure 1 is a perspective view showing the egg holder of the present invention.

75 Figure 2 is a side elevation of the holder showing beneath it a plate in section.

In the manufacture of egg holders in accordance with this invention, I start with a straight piece of wire and this wire is bent into a succession of loops 1. All these loops 80 are of the same size, are circular in configuration and lie in the same plane.

Each loop is provided with a shank 2 formed by bending the wire upon itself as shown and the shanks of the respective loops 85 are a continuation of one another. The free ends of this piece of wire are united as shown at 3 and there is thus provided a flat wire frame, all parts of which lie in the same plane and which frame designated generally 90 in the drawings by the reference character 4 embodies a plurality of egg supporting loops or seats formed from one continuous piece of wire.

In Figure 1 of the drawings a structure is 95 shown as adapted to support a dozen eggs although, in practice, I may make any desired number of loops as circumstances may warrant.

When the frame 4 is bent up as stated, the 100 loops are carefully formed into proper circular contour. It is essential, however, that the wires which form the shanks of each of these loops be firmly bound together in order that this contour may be maintained. I accomplish this result in a novel and economical way by having the legs 5 which support the frame serve the dual purpose of the support and fastening means. This is accomplished 105 in the following manner.

110 The feet of the device are formed of wires 5 which are bent into substantially U shaped

configuration, so as to lie on a flat surface. The free ends of these wires are bent upwardly for a distance which it is desired to support the frame 4 above such surface and 5 said free ends of the feet wires are thereupon coiled around the shanks 2 of the frame loops as shown at 6. This coiling of the feet wires around the loop shanks not only serves to bind the loops in closed condition, but also 10 serves to anchor the feet to the frame. If the wire used in the manufacture of the device is fairly heavy, this arrangement will of itself insure the proper relationship between the parts without further reinforcing although 15 in the use of lighter wire, I preferably provide a reinforcing ring 7 adapted to lie upon the horizontal portions of the feet exteriorly of the vertically extending portions thereof, and this wire is bound to each foot of either 20 coiling part of the foot wire around the reinforcing ring 7, or by securing the parts together by an independent binder ring 8, as shown.

The handle which I have illustrated as associated with the frame embodies three inverted U-shaped bails 9, 10 and 11. The lower ends of each bail are coiled around the loops 1, as shown, to firmly anchor the bails to the loops and all the bails are brought together and a coil of wire 12 caused to embrace all three bails as shown to bind them firmly together and form a convenient handle.

As a part of the device, I preferably associate therewith a plate 14. This is preferably of metal and of a size so that when the eggs are removed from the water after boiling, the device may be set upon this plate, so that any water which may drip will be caught by the 35 plate. This permits the eggs to be served on the table without removing them from the holder. In practice, I generally enamel or lacquer the entire device in colors, so that the device will conform to the scheme of kitchen 40 decoration prevalent where it is to be used.

My experience with the structure which I have described has shown it to be highly efficient and durable for the purposes stated. It is simple in construction and economical 45 to manufacture and it will support one or more eggs without tilting or upsetting. All parts of this structure are so supported that they are well able to withstand wear and tear without losing their shape.

50 The foregoing detailed description sets forth the invention in its preferred practical form, but the invention is to be understood as fully commensurate with the appended claims.

60 Having thus fully described the invention, what I claim as new and desire to secure by Letters Patent is:

1. An egg holder embodying a frame constructed from a single length of wire bent to 65 form a succession of closed loops constituting

egg seats with the free ends of the wire united to one another, each loop being provided with a shank which constitutes a continuation of the shanks of the adjacent loops, and all parts of said frame lying in the same 70 plane, in combination with supporting members embodying lengths of wire bent upon themselves to form feet and the free end portions of which wires are bent upwardly and coiled about the shanks of the frame loops for 75 the purpose of maintaining said loops in closed condition and simultaneously supporting the frame above a flat surface on which the feet are adapted to rest, and a suitable handle 80 secured to the frame.

2. An egg holder embodying a frame constructed from a single length of wire bent to form a succession of closed loops constituting egg seats with the free ends of the wire 85 united to one another, each loop being provided with a shank which constitutes a continuation of the shanks of the adjacent loops, and all parts of said frame lying in the same plane, in combination with supporting members embodying lengths of wire bent upon 90 themselves to form feet and the free end portions of which wires are bent upwardly and coiled about the shanks of the frame loops for the purpose of maintaining said loops in 95 closed condition and simultaneously supporting the frame above a flat surface on which the feet are adapted to rest, a reinforcing ring 100 embracing the bent up portions of the supporting members and secured thereto, and a suitable handle secured to the frame.

3. An egg holder embodying a frame constructed from a single length of wire bent to form a succession of closed loops constituting egg seats with the free ends of the wire 105 united to one another, each loop being provided with a shank which constitutes a continuation of the shanks of the adjacent loops, and all parts of said frame lying in the same plane, in combination with supporting members 110 embodying lengths of wire bent upon themselves to form feet and the free end portions of which wires are bent upwardly and coiled about the shanks of the frame loops for the purpose of maintaining said loops in closed condition and simultaneously supporting 115 the frame above a flat surface on which the feet are adapted to rest, a suitable handle secured to the frame, and a plate shaped and proportioned to provide a support for the feet and on which the device is adapted to be 120 positioned after removal from boiling water, whereby the plate will receive the water which drips from the device.

4. An egg holder embodying a frame constructed from a single length of wire bent to 125 form a succession of closed loops constituting egg seats with the free ends of the wire united to one another, each loop being provided with a shank which constitutes a continuation of the shanks of the adjacent loops, 130

and all parts of said frame lying in the same plane, in combination with supporting members embodying lengths of wire bent upon themselves to form feet and the free end portions of which wires are bent upwardly and coiled about the shanks of the frame loops for the purpose of maintaining said loops in closed condition and simultaneously supporting the frame above a flat surface on which

the feet are adapted to rest, and a plurality of inverted U-shaped bails, the depending free ends of which are secured to the frame, and a coil of wire binding together the upper portions of the bails to form a handle.

In testimony whereof I have signed the foregoing specification.

HEINRICH HUBERT WEBER.
